UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,160,407.

Specification of Letters Patent.

Patented Nov. 16, 1915.

Application filed February 8, 1912. Serial No. 676,352.

To all whom it may concern:

Be it known that I, HARRY J. HICK, a citizen of the United States, residing at Alliance, in the county of Stark and State of Ohio, have invented certain new and useful Improvements in and Relating to Filing Appliances, of which the following is a specification.

This invention relates to filing appliances 10 adapted to receive and removably hold papers, slips, cards or memoranda for inspection, classification and keeping purposes.

For the purpose of illustration, I have, in the accompanying drawings, shown and 15 herein described one form of filing appliance embodying my invention.

Figure 1 is a front elevation of a filing 20 appliance embodying my invention. Fig. 2 is a side elevation thereof, part of the casing being broken away. Fig. 3 is a view similar to Fig. 2 showing part of the holders in a reclined position. Fig. 4 is a fragmentary view illustrating the operation of 25 the holders. Fig. 5 is a perspective view of the counterbalancing member. Fig. 6 is a fragmentary view illustrating details of construction.

In the drawings, 1 indicates a suitable casing or housing having a base or platform 30 1^a and a back or rear wall 1^b rising vertically from said base. Preferably, the forward portion of the platform 1^a consists of a glass plate 1^c, below which may be mounted a suitable index 2. The index 2 is mounted in a 35 frame 2^a, which may be slidably supported on guides 1^d that are fixed to the inner walls of the casing.

3 indicates a series of holders, arranged to be assembled face to face and adapted to 40 hold or support papers, slips and the like. The series of holders 3 comprises a front holder 3^a, a rear holder 3^b and intermediate holders 3^c. Each of said holders may consist of a sheet metal back 3^d that is preferably extended along its lower edge and bent on longitudinal lines to form a hinge bar 3^e.

3^f indicates plates extending along the opposite sides of each back 3^d. These plates form side walls for the holders and also 50 spacing devices between them, thereby determining the amount of space on either side of each back 3^d that may be utilized for the papers or slips to be filed. As the holders are preferably of uniform size, it will be 55 understood that the longitudinal edges of

the side plates 3^f of one holder engage the longitudinal edges of the adjoining holders.

The upper end of each holder 3^c may be provided with incline plates 3^g and carry suitable indexes 3^h. The index plates 3^g may be cut away, as shown at 3ⁱ, to expose the index 3^h on the plate of the next rearward holder.

4 indicates a series of strips extending from the hinge edge of each holder to its free edge, and serving to divide the adjacent back 3^d into pockets. The strips also operate to strengthen the back intermediate between its edges. As it is usual in apparatus of this character to provide strips 4 65 on both sides of each back and to aline the strips on one back with the strips on adjoining backs, it will be understood that they also serve to space the backs from each other.

5 indicates suitable paper or slip supporting devices mounted on the opposite faces of each back 3^d. Each of these devices preferably comprises a wire clip, having spring coils 5^a. The opposite ends of the wires may 70 be secured to the adjacent back 3^d.

5^b indicates a plate serving to tie the legs of the clip together. The plate 5^b also serves as a support for an eye signal, such as a number, letter, or heading.

6 indicates hinge or pivot connections between the hinge bars 3^e. These connections operate to connect the holders together and to permit them to be operated or swung relatively to each other. The connections 6 also 85 operate when one or more of the holders are reclined to move the rearward holders upwardly and their lower or hinged ends forwardly. As shown in Figs. 1 and 2, the holders 3 are normally arranged in a vertical position and swing forwardly and downwardly to a substantially horizontal position, and vice versa. The pivot connections 6 may comprise a series of plates 6^a pressed or bent to fit snugly around the hinge bars 100 3^e, the opposite free ends of each plate being riveted to the adjacent back 3^d. As indicated at 6^b, each plate 6^a is provided with a hinge loop at either lower edge.

The front holder 3^a and each alternate 105 holder is preferably provided with two hinge plates 6^a spaced from each other, while the remaining alternate holders are each provided with one hinge plate that is adapted to fit between and have its loops 6^b 110

aline with the loops 6^b of adjacent plates. A pivot pin 6^e extending through each alined set of loops serves to complete the pivotal connections 6 between the holders. 5 As shown in the drawings I prefer to provide two sets of connections 6 arranged near the opposite ends of the hinge bars 3^e .
 7 indicates a bar carried by the back 1^b . It serves as a guide or sliding abutment for 10 the upper or free edge of the rear holder 3^b in its up and down movements due to the operation of the holders forward thereof. At its free end, the bar 7 preferably carries a latch 7^a which is adapted to be engaged by 15 the free end of the holder 3^b and prevent it from being reclined. The bar 7 is preferably pivoted to the back 1^b , whereby it may fall by gravity into the position shown in Figs. 1 and 2 when the holders 3 are in normal position. In this latter position of the 20 bar 7, the latch 7^a thereof will lie in front of the free edge of the holder 3^a . The effect of this arrangement will be to lock the said holder and all the remaining holders against 25 operation. The front holder 3^a may be released by pressing the bar 7 slightly upward. If now the front holder is reclined it will elevate all the remaining holders. The elevation of the rear holder will thus raise 30 the bar 7 and move its latch 7^a above the free edges of those holders now in vertical position.

The bar 7 will be maintained in its elevated position as long as the front holder 35 is reclined and will operate as guide and paralleling means for the holders as they are operated.

8 indicates means for supporting the 40 series of holders 3 in a manner which permits one or more of them to act as a counter-balance for the remaining holders; the advantages of this construction being to facilitate the ready operation of the holders and to reduce the manual force or labor required to manipulate them.

The supporting means 8 preferably comprise a rocker or lever 8^a , the fulcrum of which is preferably nearer to its front end than to the rear end thereof.

50 8^b , 8^c , indicate a pair of standards which are preferably integral turned-up members of a plate 8^e , the latter being fixed by suitable screws to the base 1^a .

8^d , 8^e , indicate trunnions which loosely fit 55 within suitable bearings formed in the standards 8^b and form the fulcrum for the rocker 8^a . At its front end, the bar 8^a is provided with two spaced vertical walls 8^e , 8^e , which form between them a recess 8^f to

60 receive a pivot pin 6^f extending through the hinge loops 6^b of the hinge plate 6^a at the front edge of the holder 3^a . The recess 8^f and pin 6^f form a pivotal connection between the rocker and the end holder 3^a at 65 the front of the series, and about which the

holder 3^a swings. This connection also permits ready detachment of the series of holders 3 from the rocker 8 and from within the casing 1 for storage in a safe place.

The hinge bar 3^e for the front holder 3^a 70 is formed with openings 3^e which receive the free ends of the walls 8^e when the said holder is in either a normal or a reclined position.

As shown in Figs. 1 and 2, the series of 75 holders 3 being connected to the front end of the rocker 8, the rear end of the latter will be forced upwardly into engagement with the hinged ends of the holders 3^e , while the rear holder 3^b will rest at its free 80 end against the back 1^b , or a yielding device 1^b which may be carried thereby. The front holder 3^a being pivotally connected to the front end of the rocker 8^a , the hinged edges of the holders 3^e and 3^b will slide 85 forward and rearward on the rear end of the rocker 8, as the holders are individually or collectively operated in one direction or the other. The arrangement and construction is preferably such that when 90 the holders are in normal position comparatively little counterbalancing effect is produced; but, as soon as the front holder 3^a is operated forwardly, the intermediate 95 holders will be elevated so that the opposite end holders will rest upon and be supported by the opposite ends of the lever 8^a . Such operation will move the hinged edges 100 of the holders forwardly and thus shift their weight relative to the fulcrum of the supporting lever. As each succeeding 105 holder is swung forwardly, the weight on the front end of the rocker will be increased and thus result in increasing the counter-balancing effect on the rearward holders.

110 From the drawings and foregoing description, it will be understood that the rear holder 3^b moves or slides forwardly and rearwardly on the rear arm of the lever relative to its fulcrum during the operation of the holders from one position to the other and back again. Thus the distance between the lever fulcrum and the point of contact with the rear holder 3^b , which constitutes the throw of the lever, is shortened each time a 115 holder is operated from the vertical to the horizontal position and increased when the holder or holders are returned. As the weight on the front end of the lever increases and decreases materially as the holders are operated forwardly and rearwardly, the lengthening and shortening of the throw of the lever has the effect of equalizing the counter-balancing influence at all times. Preferably the lever is of a length less than 120 the depth of the series of holders. The result of this construction is that the point of contact with the rearward holders remains unchanged until a sufficient number 125 of holders have been operated to move the 130

rear holder 3^b past the rear end of the lever, so that the throw of the lever will not be decreased until the number of holders in the upright position has been considerably lessened.

As the hinged ends of the holders 3 move upwardly and downwardly as well as forwardly and rearwardly during the operation of the holders, it will be understood that if the fulcrum for the rocker were arranged midway between its ends considerable space would be required to accommodate and permit the full swing of the opposite ends of the rocker. This disadvantage is overcome by positioning the fulcrum for the rocker near one end thereof, preferably the front end, so that the rear end of the lever will have a greater throw than its front end. By this construction it will be seen that during the operation of the holders the movements of the opposite ends of the rocker will be in proportion to the relative position of its fulcrum, and that both ends of the rocker will coöperate to support the holders, permit forward and rearward, and upward and downward relative movements of the rear holder and intermediate holders during their operation and also permit certain holders of said series to counterbalance certain other holders thereof.

As will be understood in reclining each holder, all the remaining holders must be elevated. This operation requires the expenditure of considerable energy, especially when the holders are weighted down with papers or slips as the result of a large number of sales or charges. But by the employment of my device the holders are caused to equalize or counterbalance each other, thus reducing the labor to operate them and permitting quicker manipulation of the holders.

While the construction is such as to primarily counterbalance the rearward holders, it will of course be seen that the rearward holders counterbalance the forward holders so that the power required to return the holders to normal position is reduced. My construction has the further advantage of reducing the stresses on the pivot connections 6, thus obviating breakage, wear and disalignment thereof.

The movement of the lever is preferably arrested after the operation of a predetermined number of holders from the vertical position to the horizontal position by the engagement of its front end with the base 1^a, as shown in Fig. 3, it requiring but little effort to operate the remaining upright holders.

To those skilled in the art of making filing appliances of the class described, many alterations in construction and widely differing embodiments and applications of my invention will suggest themselves, without departing from the spirit and scope thereof.

My disclosures and the description herein are purely illustrative, and are not intended to be in any sense limiting.

What I claim is:—

1. The combination of supporting means, a series of connected-together holders, and a rocker on said supporting means for movably supporting the series of holders and permitting a portion of said holders to counterbalance the other portion thereof, the fulcrum for said rocker being nearer one end thereof than its other end. 70

2. The combination of supporting means, a series of connected-together holders, and a rocker on said supporting means for movably supporting the series of holders and permitting a portion of said holders to counterbalance the other portion thereof, the front end holder being pivotally connected to the rocker on one side of its pivot, the rear end holder having sliding engagement with the rocker on the opposite side of its pivot. 80

3. The combination of supporting means, a series of geared-together holders, and a rocker for supporting the opposite end holders of the series of holders and permitting a part of said holders to counterbalance the remaining part, the fulcrum for said lever being nearer its front end than its rear end. 90

4. A filing appliance including a support, a rocker arm mounted on said support, and a plurality of holders hinged together at their lower ends normally mounted in upright position on said arm, the foremost holder being pivoted on one end of said arm and the rearmost holder being slidably mounted on the other end of said arm to permit a portion of said holders to counterbalance the other portion thereof. 100

5. A filing appliance including a support, a rocker arm mounted on said support, and a plurality of holders hinged together at their lower ends and normally mounted in upright position on said arm, the fulcrum for said arm being nearer one end thereof than the other to counterbalance the leaves as they are operated from upright to reclined position, and vice versa. 110

6. A filing appliance including a support, a rocker arm mounted on said support having its fulcrum nearer one end thereof than the other, a plurality of holders hinged together at their lower ends normally mounted in upright position on said arm, the foremost holder being pivoted on the end of said arm nearest its fulcrum and the rearmost holder being slidably mounted on the other end of said arm, whereby a portion of said holders may be counterbalanced by the other portion thereof. 120

7. A filing appliance including a support, a rocker arm mounted on said support having its fulcrum nearer one end thereof than the other, a plurality of holders hinged to- 130

gether at their lower ends normally mounted in upright position on said arm, the foremost holder being pivoted on the end of said arm nearest its fulcrum and the rearmost holder being slidably mounted on the other end of said arm whereby a portion of said

5 holders may be counterbalanced by the other portion thereof, and means for guiding the

rearmost holder in its up and down movements.

In testimony whereof I affix my signature, in the presence of two witnesses.

HARRY J. HICK.
